UNITED STATES PATENT OFFICE.

THEODOORUS HUBERTUS GERAERDTS, OF NEW YORK, N. Y.; JEAN H. GERAERDTS AD-
MINISTRATRIX OF SAID THEODOORUS HUBERTUS GERAERDTS, DECEASED.

REINFORCEMENT OF PLASTER BLOCKS.

Application filed August 21, 1923. Serial No. 658,513.

This invention relates generally to the art of masonry and has specific reference to a particular form of building block or unit adapted to be used in the wall construction 5 of elevator shafts, dumb-waiter shafts, fan or ventilating shafts, and the like.

An important object of the invention is to provide a block or unit of the character mentioned so constructed as to form mortar 10 receiving pockets adapted for the reception of reinforcing elements and a keying material when the units are arranged in an end to end relation, or in a perpendicular or other angular relation such, for example, as 15 is required in wall corners.

Other objects and certain advantages of the invention will become apparent from the following description taken in connection with the accompanying drawings in 20 which,

Figure 1 is a top plan view of a portion of a straight wall construction employing the units embodying my invention.

Figure 2 is a top plan view of a portion 25 of angularly disposed adjoining walls employing units embodying my invention.

Figure 3 is an end view of one of the units shown in Figures 1 and 2.

Figure 4 is a side elevation of a tie.

30 In the drawings wherein for the purpose of illustration, is shown what I at present consider the preferred form of my invention, the numeral 5 indicates a portion of a straight wall construction made up of a plurality of blocks or units 6 adjoined in an end to end relation. These units are formed of plaster Paris composition or other suitable material and are provided upon opposite edges with longitudinal grooves 7.

40 When the blocks are superimposed one upon the other, as shown in Figure 3, the grooves 7 register with each other and by reason of such registration form mortar receiving passages 8 adapted for the retention of mortar 45 or other cementing material 9. This mortar or cementing material, as will be readily appreciated, is applied to the grooved faces of the units 6 as the building of the wall progresses, and thus by reason of the presence 50 of the mortar or cementing material within the passages 8, the units are effectively keyed or locked together.

In order that a suitable mortar or cementing material may be introduced between

the adjacent ends of the blocks after the same have been placed in position within a plain or straight wall construction, I have so grooved the ends of the units that the registering grooves will form pockets or cement cavities into which the cementing material may be introduced from the face of the wall. These grooves are indicated by the numeral 10 and form with each other pockets or cement cavities 11 into which the cementing material 12 may be introduced 55 from the side of the wall through a throat or restriction 13 formed intermediate the beveled faces 14 of the adjoining units. Adjacent each groove 10 of each block or unit, there is formed a projection or wing 15 the faces 16 of which meet in an angular relation when the units are employed in a straight wall construction such as is illustrated in Figure 1. If desired, tie-rods 17 60 may be incorporated into the cementing material 12 as an additional reinforcement for the wall construction in its entirety. These tie-rods as will be readily appreciated, are placed in position within the pockets 11 before the cement 12 is introduced, and upon 65 hardening of the cement they become, in effect, an integral part thereof. It will be noted that the grooves 10 are so formed as to mould the cement 12 into a key 12' provided with indentures 18 into which fit the 70 wings 15 thereby interlocking the units 6 with the moulded cement key in such a way that it would be impossible to move one of the blocks longitudinally with respect to the other in separating the same without 75 breaking the wings 15, adjacent the faces 16, from their respective units.

Referring now to Figure 2, wherein is shown adjoining angularly disposed walls employing units embodying my invention, 80 it will be noted that the wings 15 are maintained in a spaced relation, whereas the opposite corners of the sections join each other, as shown at 19. The faces 14 of the units are so inclined or beveled with respect 85 to the units themselves that they lie in diverging planes when the units are joined, as shown in Figure 2, thus affording spaces 90 which communicate with the pockets or cement cavities 21 formed by reason of the presence of the grooves 10. As previously 95 mentioned, the wings 15 in the case of angularly disposed adjoining walls, are separated 100

and thus permit access to be gained to the pockets 21 through the throats 22 formed therebetween.

The cementing material 12 in the case of 5 such a wall as is shown in Figure 1, is introduced through the throat 13 formed intermediate the beveled faces 14, but in the case of angularly disposed adjoining walls, the cementing material 12 is introduced 10 through the throats 22 thereby filling the spaces 20 and the pockets 21. Upon introducing material into the pockets 21, keys 22' are formed having fins 23 which fit into the spaces 20 afforded between the beveled faces 14. The keys thus formed are provided 15 with ribs 23' having indentures 24 into which fit the corners 25 of the units 6. It will be appreciated from this construction 20 that the units are prevented from moving in the direction of the arrows *a* by reason of the engagement of the corners 25 with the ribs 23'; and it will also be appreciated that the units are prevented from moving longitudinally in the direction of arrows *b* by 25 reason of the fact that the wings 15 are fitted into the indentures 24 and engage the ribs 23'.

If desired, tie-rods 17 may also be employed in connection with the wall shown 20 in Figure 2, which tie-rods are, as previously mentioned, placed in position before the cementing material is introduced and are thereafter held by reason of the hardening 25 of the material around the same. In the case of a shaftway construction employing, as shown, four side walls and four corners, a tie-wire 27 may be arranged within the grooves 8 intermediate the several sections. This tie-wire is preferably passed 40 around the tie-rods 17, as shown in Figure 2, and function, as is obvious, to reenforce the structure in its entirety, thus lending

rigidity to the same and insuring safety. In the case, however, of a straight wall construction, the tie-wire may be omitted and 45 ties 28 substituted therefor. These ties are relatively short and are provided with hooks 29 which are driven or otherwise imbedded into the blocks upon opposite sides of the joints formed therebetween, thus 50 lending rigidity and strength to the structure as a whole.

While I have shown and described what I at present consider the preferred form of my invention, it is to be understood that 55 various changes in the same as to certain details of construction may be resorted to without departing from the spirit of the invention or the scope of the subjoined claim.

I claim:

In a wall structure, a pair of wall units arranged in an adjacent relation, each of said units being provided at its end with a groove, the grooves of said units forming with each other a cement cavity between said units, each of said units being provided with a face adjacent said cavity, said faces being spaced from each other and forming with each other a throat leading from said cavity to the exterior of said wall structure, 70 a wing carried by each of said units adjacent its groove and projecting into said cavity, a key arranged within said cavity and provided with a solid portion in said throat and formed with ribs arranged with 75 in said grooves and provided with indentures adjacent said ribs, said wings projecting into said indentures and cooperating with said ribs to prevent separation of one unit from the other.

In testimony whereof, I have affixed my signature to this specification.

THEODOORUS HUBERTUS GERAERDTS.
